UNITED STATES PATENT OFFICE.

RICHARD E. MANN, OF NEW BRIGHTON, NEW YORK.

DESIGN FOR A THERMOMETER.

Application filed September 1, 1926. Serial No. 18,917. Term of patent 7 years.

To all whom it may concern:

Be it known that I, RICHARD E. MANN, a citizen of the United States, residing in New Brighton, in the county of Richmond and State of New York, have invented a new, original, and ornamental Design for a Thermometer, of which the following is a specification, reference being had to the

accompanying drawing, forming a part thereof.

The figure is a perspective view of a thermometer showing my new design.

I claim:

The ornamental design for a thermometer as shown.

RICHARD E. MANN.
